UNITED STATES PATENT OFFICE.

ARTHUR C. BLACKBURN AND BERT B. SHIEK, OF VINCENNES, INDIANA; SAID BLACKBURN ASSIGNOR TO EDWARD SHIEK, OF VINCENNES, INDIANA.

CURTAIN-POLE AND WINDOW-SHADE HANGER.

1,118,625.

Specification of Letters Patent. Patented Nov. 24, 1914.

Application filed June 18, 1914. Serial No. 845,902.

To all whom it may concern:

Be it known that we, ARTHUR C. BLACKBURN and BERT B. SHIEK, citizens of the United States, residing at Vincennes, in the county of Knox and State of Indiana, have invented a new and useful Improvement in Curtain-Pole and Window-Shade Hangers, of which the following is a specification.

This invention is a combination curtain pole and shade roller support, designed especially for ready clamping upon a window casing, and for quick removal therefrom, no nails or screws being employed for the purpose of attaching the holder to the casing.

15 The invention also consists in the novel features of construction hereinafter described, pointed out in the claim and shown in the accompanying drawings, in which,

Figure 1 is a face view of one of the holders in position, a curtain pole and shade holder and a portion of a shade being indicated in dotted lines. Fig. 2 is a top plan view of the holder in position, a window casing being shown in section. Fig. 3 is an 25 end view of the holder detached. Fig. 4 is a transverse section through the holder, a shade roller support being also shown in section and partly in elevation.

It will be understood that two of these devices are employed in connection with each window, but as they are duplicates only one has been illustrated.

The device consists of a plate 1 longitudinally slotted as shown at 4, and one end of said plate is bent at a right-angle, and is provided with tongues 3 bent upon themselves to form prongs which are adapted to bite into the window casing. A plate 5 similar in size to the end portion 2 of the plate 40 1 is carried by said plate at a right-angle thereto and is slidable along the slot 4. The plate 5 also carries tongues similar to those at 3 and these bite into the opposite side of the window casing. The plate 5 is moved

toward and away from the casing and along the slot 4 by a feed screw 6 which works through said plate and turns loosely in the end 2, being provided upon its outer end with a suitable thumb-piece 7. Clamped to the plate 1 and also slidable along the slot 4 for purposes of adjustment is a curtain pole holder 8 and a shade roller holder 9, these 50 holders being secured in position by means of headed pins 12 upon which work nuts 11, the pins passing through the slot 4.

To clamp the device in place it is simply necessary to rest the plate 1 against the face of the casing with the prongs of the tongue 3 in engagement with the outer side of the casing, and then rotate the screw 6 so as to 60 draw the plate 5 tightly against the inner side of the casing, until the prongs bite sufficiently into the wood. The holders 8 and 9 may then be properly adjusted relative to each other and the device is ready 65 for use. It can be removed at any time by simply reversing the screw 6 thereby 70 drawing the plate 5 away from the window casing.

What we claim is:

A support for curtain rods and shade rollers comprising a longitudinally slotted plate having a bent end portion provided with biting tongues, a plate arranged at right angles to the first mentioned plate, 75 said plate engaging and being slidable along said slot, a feed screw working through the second mentioned plate and journaled in the bent end portion of the first mentioned plate, biting tongues carried by the second mentioned plate, and means supported from the first mentioned plate for holding a curtain rod and a shade roller.

ARTHUR C. BLACKBURN.
BERT B. SHIEK.
